UNITED STATES PATENT OFFICE

ERNEST JAMES SMITH, OF FLEET STREET, LONDON, ENGLAND, ASSIGNOR TO GOSS
PRINTING PRESS COMPANY, A CORPORATION OF ILLINOIS

WEB CONTROLLING APPARATUS

Application filed January 3, 1930, Serial No. 418,379, and in Great Britain January 11, 1929.

The present invention relates to web controlling apparatus and more particularly to an improved web controlling apparatus for use in connection with high speed rotary printing machines.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is an end elevation, with certain parts broken away, of the present preferred embodiment of web controlling apparatus and illustrating the present invention; and

Figure 2 is a horizontal section taken on the line 2—2 of Figure 1, with certain parts broken away.

The present invention provides a web controlling mechanism for tensioning the web as it is drawn from a web roll and fed to a printing press, and has for its particular object the provision of a simple, reliable web controlling mechanism which will not interfere with the operation of replenishing the web rolls as they become exhausted. Another object of the present invention is the provision of a web controlling mechanism producing a substantially constant predetermined web tension, regardless of the diameter of the web roll and yet permitting the constant tension to be readily varied to meet different press operating conditions.

According to the present preferred embodiment, illustrating the invention, there is provided a web roll support for rotatably supporting the relatively large and heavy rolls of paper commonly used to supply the printing press, and means are provided for raising and lowering the web roll support,

as well as for holding the web roll support in any desired position, thereby enabling the web roll to be lifted from a truck into running position. For tensioning the web as it is drawn from the web roll by the printing press, there are preferably provided a plurality of flexible friction members or belts, rigidly secured at their lower ends directly beneath the web roll, and fastened at their upper ends to movable rollers above the web roll. Means are provided for pressing the flexible belts into contact with the web roll and for maintaining the belts in contact with the periphery of the web roll, and in the present embodiment there is provided a weighted arm and gear connected with the rollers to which the upper ends of the belts are fastened, which moves the rollers, winds the belts on the rollers as the web roll wears down, and thereby maintains the tension of the web constant. Other means are provided for retaining the weighted arm in a raised position to relieve the tension on the belts, and to permit the fastening means for the lower ends of the belts to be displaced from its normal position, thereby facilitating the replacement of the web roll. In the embodied form, the weight for tensioning the belts is minutely variably positionable on its supporting arm and thereby enables the constant tension created by the belts to be readily varied to suit the different operating conditions of the press. Means are also preferably provided for variably positioning the web roll transversely of the line of feed of the web to register the web with the cylinders of the printing press to which the web is fed.

It will be understood that the foregoing general description, and the following detailed description as well, are exemplary and explanatory of the invention but are not restrictive thereof.

Referring now in detail to the accompanying drawings showing the present preferred embodiment and illustrative of the present invention, the web roll supporting means preferably comprise a pair of supporting arms 10 slidably keyed to a supporting shaft 11 extending from one side frame 12 of the press to the other side frame 13. Supporting

arms 10 preferably extend on each side of the supporting shaft 11 to support an active and a reserve web roll, 14 and 15 respectively, and at their ends are provided with short spindles 16 and 17, rotatably journaled in suitable bearings near the ends of the arms 10, each pair of spindles being adapted to engage a web roll at either end of its axial aperture. Arms 10 are preferably slidable 10 along their supporting shaft 11 to accommodate web rolls of different widths, and are securely held in the desired position by any suitable means, such as set screws, or the like.

For facilitating the replenishment of web 15 rolls, as they become exhausted, the supporting shaft 11 and arms 10 carried thereby, are preferably angularly movable to raise and lower the web rolls, thereby enabling web rolls to be lifted from the truck 18 on 20 which they are brought to the supporting mechanism, as needed. These means preferably comprise a segmental worm gear 20, rigidly fastened to one end of the supporting shaft 11 and movable therewith, the segment 25 meshing with a worm 21 rotatably journaled in a bracket 22 mounted on the upright side frame 12. For turning the worm to angularly move the web roll supporting arms, there is provided a bevel gear 23 meshing 30 with bevel gear 25 fixed to the worm shaft 24 and movable therewith, and handle 26 is provided connected with the bevel gear 25 for manually turning the worm. The worm and worm gear also serve to lock and hold 35 the web roll supporting arms in any desired position.

Preferably, and as embodied, one of the rotatable spindles 16, for each web roll is axially movable to allow the stub of an exhausted web roll to be removed and replaced by a fresh web roll, and other means are preferably provided for holding the spindle in engagement with the axial aperture of the web roll while the web roll is actively 45 supported. The details of these parts are not shown, as they form no part of the present invention, and they may be of any convenient or suitable construction.

For registering the web with the cylinders 50 of the printing press the web roll supporting arms are preferably movable axially of the web roll, and in the present embodiment, the supporting shaft 11 is slidably mounted in 55 its journals in the side frames 12 and 13 and is moved to and held in any desired position by means of threaded shaft 27, which cooperates with an internally threaded portion of the shaft 11, while shaft 27 is held 60 against axial movement in its supporting bracket 28. Directly beneath segmental worm gear 20 is provided a channel 29 in which the lower part 30 of the worm segment rotates, and which holds the segmental worm 65 gear against axial movement, permitting it

to slide on the supporting shaft 11 as the shaft is axially moved.

The web tensioning means in accordance with the present invention preferably comprises a plurality of flexible friction members, or belts 32, adapted to bear against the periphery of the web roll and to be maintained in contact therewith. These belts are preferably suitably spaced apart along the web rolls and are secured at their lower ends to anchoring arms 34, pivotally mounted on the rigid base 35 and extending beneath the web roll for a considerable distance. Anchoring arms 34 are each provided with an inwardly extending portion 36, cooperating with a stop 38 to limit the upward movement of the arms and belts. The upper ends of the flexible belts 32 are firmly attached to the periphery of individual rollers 39 and adapted to be wound thereon.

For tensioning the web and maintaining the tension substantially constant regardless of the diameter of the web roll, means are provided for maintaining the flexible belts in frictional contact with the periphery of the web roll and for pressing them into contact therewith with a definite and predetermined, although easily variable pressure. As embodied, for each web roll there are provided a plurality of rollers 39 fixed to a shaft 40 directly above and parallel with the axis of the corresponding web roll, the shafts being rotatably journaled in pairs of depending arms 41, oscillatably supported by means of shafts 42 extending from one side frame to the other. The upper ends of the belts are fastened to their individual rollers and can be wound thereon to press the belts into contact with the periphery of the web roll and to maintain them in contact therewith, and the individual rollers are preferably aligned with the pivoted anchoring arms 34 to which the lower ends of the belts are attached. At one end of each roller shaft there is provided a small pinion 44 meshing with a segmental gear 45 concentric with its corresponding shaft 42 and securely fastened to the side frame by bolts 46, so that as the roller supporting arms 41 oscillate, the rollers 39 wind and unwind the belts.

For moving the rollers to maintain the belts in contact with the web rolls and at a constant pressure, weights are preferably provided to roll the pinion over the stationary segmental gear, and in the illustrative embodiment, there is provided a threaded arm 50, rigidly attached to each roller supporting shaft 42 by means of collar 51, and this arm is provided with a correspondingly threaded weight 52 which can be turned to variably position it along its arm 50 for varying the turning moment applied to the rollers 39, and consequently the pressure between the belts and the web roll, thereby varying the tension of the web. To secure a substan-

tially equal turning moment throughout all positions of the rollers 39, the threaded arms 50 project substantially horizontally from their shafts 42 and move through only a relatively small arc.

As shown in the present illustrative embodiment, the anchoring arms 34 for the lower ends of the belts 32, and the rollers 39 to which the upper ends of the belts are fastened are preferably so positioned, and the distance through which the rollers move and the direction of their movement is such that the angle measuring the arc of the area of contact between the belts 32 and the periphery of the web roll remains substantially constant regardless of the diameter of the web roll.

For holding the belts slackened, as is necessary when a new web roll is to be placed in running position, means are preferably provided for retaining the weights in a raised position, and collars 51 are preferably provided with a notch 54, cooperating with a dog 55 pivoted above the collar, and adapted to drop into and engage the notch when weight 52 is lifted into its extreme upper position, as shown at the right of Figure 1. This slackening of the belts also allows the anchoring arms to which the lower ends of the belts are fastened to drop out of the way of the truck 18 on which a new web roll is brought into position before being engaged and supported by the spindles 16 and 17.

In case of a break in the web, as it is being drawn from the web roll by the printing press, the operator can easily apply his weight to weight 52 or the weight supporting arm 50, thereby greatly increasing the pressure between the belts and the web roll and quickly bringing the web roll to a stop.

The invention in its broader aspects is not limited to the specific mechanisms shown and described but departures may be made therefrom within the scope of the accompanying claims without departing from the principles of the invention and without sacrificing its chief advantages.

What I claim is:—

1. Web controlling mechanism for use with printing presses including in combination angularly movable arms for rotatably supporting a web roll and means for tensioning the web as it is drawn from the web roll by the press including a flexible friction belt adjacent to the axis of the arms to bear against the periphery of the web roll, a roller to which the belt is fastened, a weighted arm and gear connected with the roller for turning the roller for maintaining the belt in contact with the periphery of the web roll and means for raising and lowering the angularly movable arms.

2. Web controlling mechanism for use with printing presses including in combination angularly movable arms for rotatably sup-

porting a web roll and means for tensioning the web as it is drawn from the web roll by the press including a flexible friction belt adjacent to the axis of the arms to bear against the periphery of the web roll, a roller to which the belt is fastened, a variably positionable weight for turning the roller to maintain the belt in constant engagement with the periphery of the web roll and means for raising and lowering the angularly movable arms.

3. Web controlling mechanism for use with printing presses including in combination means for rotatably supporting a web roll and means for tensioning the web as it is drawn from the web roll by the press including a flexible belt adapted to bear against the periphery of the web roll, a support to which one end of the belt is fastened, means permitting the support to be moved out of the path of a web roll as the web roll is replenished, a roller to which the other end of the flexible belt is fastened, a weighted arm for turning the roller to tension the belt and maintain it in contact with the surface of the web roll with a constant pressure, means for variably positioning the weight on the arm, and means for retaining the weight in raised position during replenishment of the web roll, and means for raising and lowering the web roll support to lift a web roll into running position.

4. Web controlling mechanism for use with printing presses including in combination means for rotatably supporting a web roll and means for tensioning the web as it is drawn from the web roll by the press including a flexible belt, a roller to which one end of the belt is attached, and means for moving the roller to maintain the belt in contact with the periphery of the web roll throughout a substantially constant angle.

5. Web controlling mechanism for use with printing presses including in combination means for rotatably supporting a web roll and means for tensioning the web as it is drawn from the web roll by the press including a flexible belt, a roller to which one end of the belt is attached and means for moving the roller and for winding the belt on the roller to maintain the belt in contact with the periphery of the web roll throughout a substantially constant angle measured on the web roll.

6. Web controlling mechanism for use with printing presses including in combination means for rotatably supporting a web roll and means for tensioning the web as it is drawn from the web roll by the press including a flexible belt and means for maintaining the belt in contact with the periphery of the web roll and for exerting a substantially constant pressure between the belt and the web roll and for maintaining the angle of

4

contact of the belt and web roll substantially constant.

7. Web controlling mechanism for use with printing presses including in combination means for rotatably supporting a web roll and means for tensioning the web as it is drawn from the web roll including a flexible belt having its ends attached to supports, one of which is a roller, means for winding said belts on said roller to maintain them in contact with said roll and means for moving one of said supports as the web roll wears down to maintain substantially constant the angle of contact between the roll and belts as measured on said roll.

In testimony whereof, I have signed my name to this specification.

ERNEST JAMES SMITH.
